UNITED STATES PATENT OFFICE.

CHARLES G. BAUER, OF GLENDALE, NEW YORK, ASSIGNOR TO BAUER MANUFACTURING COMPANY, INC., OF QUEENS COUNTY, NEW YORK, A CORPORATION OF NEW YORK.

CURTAIN-FASTENER.

1,323,950.

Specification of Letters Patent.

Patented Dec. 2, 1919.

Application filed January 23, 1918. Serial No. 213,342.

To all whom it may concern:

Be it known that I, CHARLES G. BAUER, a citizen of the United States, residing at Glendale, in the county of Queens and State of New York, have invented new and useful Improvements in Curtain-Fasteners, of which the following is a specification.

This invention relates to improvements in curtain fastening devices.

10 In carrying out my invention it is my purpose to produce a simple and cheap construction of fastening devices whereby a curtain may be readily fastened to a suitable frame or other structure and effectively held in such fastening condition, while at the same time the said curtain may be easily and quickly released when desired.

15 It is also my purpose to produce a curtain fastening means including a member having a laterally extending head and to arrange a spring means between the ends of the shank and the extending portions of the head, said springs designed to engage with the opposite edges of the eyelet upon the curtain to hold the same against accidental removal when engaged thereby.

20 With the above and other objects in view the improvement resides in the construction, combination and arrangement of parts set forth in the following specification and falling within the scope of the appended claims.

25 In the drawings:

Figure 1 is a perspective view illustrating the application of the improvement.

30 Fig. 2 is a central longitudinal sectional view on a greatly enlarged scale and taken approximately on the line 2-2 of Fig. 1.

35 Fig. 3 is a transverse sectional view approximately on the line 3-3 of Fig. 2, and

40 Fig. 4 is a perspective view of the elements comprising the eyelet.

45 Referring now to the drawings in detail, the numeral 1 designates a portion of the frame or other support upon which the catch member, constructed in accordance with my invention, is attached. The catch includes a base plate 2 which is provided with parallel slots 2' which receive therein fingers 3' formed on the inner edges of the 50 sides 3 of the catch member or button. The fingers are secured in the slots in any preferred or desired manner. The sides 3 at the outer corners thereof are enlarged or

provided with longitudinal extensions 4, the outer edges of the said extensions being 55 rounded. These extensions 4 provide the ends of the head 5 of the catch or button. Preferably the head 5 is integrally formed with the side 3 as disclosed by the drawings. It will be thus noted that the head comprises 60 a hollow member and the spaced sides 3 provide a shank for the head.

Arranged in the catch member or button between the sides and the head thereof is a flat spring 6 that has its ends rounded, as 65 at 7, the said rounded ends being disposed in the space between the ends of the shank and the ends of the head, the ends of the said spring contacting with the base 2. The ends of the spring engaging with the 70 rounded ends of the head have the effect of bowing the springs at the portions thereof arranged between the head and the base, and the said bowed ends of the spring are adapted to frictionally engage with the opposite edges of an eye member 8 that is secured to the curtain 9, whereby to effectively 75 lock the eye to the catch.

The eye 8, in the showing of the drawings, comprises two flat washers 9' and 10 80 respectively. Both of the washers are provided with central openings, the opening in the washer 10 being of a materially less size than that in the plate 9'. The washer 10 is slotted at outward angles from the corner of 85 its opening and the metal bounded by these slits is bent, and these bent portions are designed to pass through an opening in the curtain 9 which is provided therefor, the ends of the said bent portions being also 90 passed through the opening in the washer 9' and bent around the outer face of the said washer.

The opening in the eye member is of a length only slightly greater than the length 95 of the shank of the catch member but is of a less length than the head of the said catch. In connecting the catch to the eye, the eye is held at an angle with respect to the catch to arrange the same in contact 100 with one of the bowed ends of the spring beneath the shoulder at the corner of the head. The eye is then moved longitudinally over the catch until the opposite end thereof is brought beyond the second end of the 105 head of the catch, when the eye is moved

toward the base 2. The bowed ends of the spring 7 then fully expand and arrange the eye in the position illustrated in Figs. 1 and 2 of the drawings. A substantially similar action is required in removing the eye from the catch, as will, it is thought, be understood.

From the foregoing description, when taken in connection with the drawings it will be noted that the eye is effectively held by the spring and being of a length less than the length of the head cannot be removed from the catch in a lateral direction except when the eye is tilted or canted, and it is believed the simplicity and advantages of the construction will be apparent without further description.

Having thus described the invention what I claim is:

- 20 1. In a curtain fastening means, a catch member including a shank having a head extending longitudinally beyond the ends thereof, spring means between the shank and the head, an eye having a slot of a length slightly in excess of the length of the shank and less than the length of the head designed to be canted over the head and to be arranged on the shank and to be engaged by the spring means to hold the same under-
30 lying the head of the catch.
2. In a curtain fastening means, a catch and an eye designed to be received by the catch, said catch including a base, a hollow shank and a hollow head which extends be-
35 yond the ends of the shank, and a flat spring in the catch contacting between the base and the head and having its ends rounded by such contact below the project-
40 ing ends of the head, and said spring de-
signed to engage the eye to hold the same on the base beneath the rounded ends of the

said spring and in underlying position with respect to the projecting ends of the head.

3. In a curtain fastening means, the combination with an eye and a catch designed to receive the eye, said catch including a base having parallel sides extending therefrom and the outer corners of the sides projecting beyond the ends of the shank, and the outer ends of the said projections rounded, a plate, comprising a head ar-
45 ranged over the outer edges of the shank and the rounded edges of the projecting edges thereof, a flat spring freely arranged in said catch and having the ends thereof 50 contacting with the base and engaging with the head and the rounded ends of the said head whereby the opposite sides of the spring are rounded by virtue of such con-
55 tact beneath the outer ends of the head, the 60 eye being of a length slightly greater than that of the shank and less than that of the head and designed to be canted over the head and arranged upon the shank and to be contacted by the bowed ends of the 65 spring when in such position.

4. In a curtain fastening device, a catch including a hollow member which is sub-
stantially T-shaped in side elevation and which has the corners of its outer member 70 rounded, and a flat spring freely arranged in said hollow member contacting between the rounded ends of the head and the base of the catch to bow the springs beneath the ends of the head, an eye member adapted 75 to be arranged on the catch and to be contacted by the bowed ends of the spring to hold the same beneath the head of the catch.

In testimony whereof I affix my signature.

CHARLES G. BAUER.
